UNITED STATES PATENT OFFICE.

JOSEF VICTOR FASSMANN, OF VIENNA, AUSTRIA-HUNGARY, ASSIGNOR OF THREE-TENTHS TO FIRM OF A. MARTINCOVICS, OF TEPLITZ, AUSTRIA-HUNGARY.

SIPHON-HEAD FOR SODA-WATER BOTTLES OR THE LIKE.

SPECIFICATION forming part of Letters Patent No. 710,674, dated October 7, 1902.

Application filed August 5, 1901. Serial No. 70,972. (No model.)

To all whom it may concern:

Be it known that I, JOSEF VICTOR FASSMANN, a subject of the Emperor of Austria-Hungary, residing at Vienna, in the Province of Lower Austria, in the Empire of Austria-Hungary, have invented certain new and useful Improvements in Siphon-Heads for Soda-Water Bottles or the Like; and I do hereby declare the following to be a full, clear, and exact description of the invention, such as will enable others skilled in the art to which it appertains to make and use the same, reference being had to the accompanying drawing, and to letters of reference marked thereon, which forms a part of this specification.

This invention relates to siphon-heads for bottles containing soda-water and other effervescent beverages; and it consists, essentially, of a part permanently connected with the bottle and containing a closing-valve and the siphon-tube and to which is removably secured an upper part or top portion carrying the delivery-tube and the discharge-lever. With this improved arrangement it is now possible to use one such upper portion in succession on any number of filled siphon-bottles, and thus effect considerable economy by merely having to supply to consumers a single top portion with the required number of filled siphon-bottles fitted only with the lower part, containing the closing-valve and the tube, as hereinbefore stated.

The accompanying drawing represents in vertical section the upper part of a soda-water bottle provided with the improved siphon-head.

According to my invention the lower portion of the siphon-head, which may advantageously be permanently secured to the bottle-neck, consists of a bush *d*, securely attached to the bottle-mouth by means of a suitable sleeve *e*, composed of two halves, and of a ring *f*, which latter forces the lower flange of the sleeve *e* under the flange or shoulder of the bottle, a tight joint being obtained by means of an appropriate rubber or other packing-ring *m*.

The bush *d* is formed with an internal seat for a ball-valve *c*, adapted to be pressed upwardly against the seat by means of a spring *b*, the valve-seat consisting advantageously of a rubber or like ring *n*. To the lower end

of the bush is secured, preferably by screwing into the interior thereof, a socket *k*, within which the spring *b* is arranged and in which the upper extremity of the siphon-tube *a* is fixed, the arrangement being such as to close the siphon-tube *a* by means of the ball-valve *c* against escape of the contents of the bottle. The removable top portion *j*, adapted to engage in a suitable internally-screw-threaded portion of the bush *d*, is furnished with a packing-ring or washer *l*, thus insuring a tight joint between these two parts.

The general construction and arrangement of the upper portion of the siphon-head is the same as usual, with the exception that it is minus the valve.

The plunger or rod *g*, operated by the discharge-lever *h* against the pressure of the spring *i*, is extended downwardly, so as to enable it to act against the ball-valve *c* when the top part *j* is screwed upon the bottle. Thus the filled bottles can be transported without the top portion *j*, as the ball-valve *c* prevents the escape of the gas with which the liquid is charged, and when the bottle is required for use it is only necessary to screw on the upper portion *j* of the siphon-head and then depress the lever, so as to open the valve and discharge the contents. On releasing the lever the spring *b* closes the valve *c* again.

I claim—

A siphon-bottle comprising a flanged neck, a bush seated therein, a flanged sleeve adapted to engage the bush and the neck-flange, a ring to hold the sleeve in engagement with said bush and flange, a socket secured to the bush, a valve-seat mounted between the bush and socket, a valve, and a spring mounted in the socket adapted to seat said valve, in combination with a siphon-head adapted to be mounted in the bush, a rod mounted in said head adapted to operate said valve, and a lever for operating said rod, substantially as and for the purpose set forth.

In testimony that I claim the foregoing as my invention I have signed my name in presence of two subscribing witnesses.

JOSEF VICTOR FASSMANN.
